(57) **CLAIM**

I claim the ornamental design for a compressible vehicle door storage organizer, as shown and described.

DESCRIPTION

FIG. 1 is a perspective view showing my new design of a compressible vehicle door storage organizer;

FIG. 2 is top plan view thereof;

FIG. 3 is front elevational view thereof, the rear elevational view being identical thereof; and,

FIG. 4 is a left side elevational view thereof, the right side elevational being identical thereof.

In the drawings, the broken lines depict portions of the article that form no part of the claimed design.
